US00D900827S

(12) **United States Design Patent** (10) Patent No.: **US D900,827 S**
(45) Date of Patent: **** Nov. 3, 2020**

(54) **INTEGRATED CIRCUIT BUILT-IN CARD**

19/0773; G06K 19/07735; G06K

(71) Applicant: **KIOXIA CORPORATION**, Tokyo (JP)

19/07737; G06K 19/07739; G06K

(72) Inventors: **Atsushi Kondo**, Kanagawa (JP); **Taku Nishiyama**, Kanagawa (JP); **Katsuyoshi Watanabe**, Kanagawa (JP)

19/07741; G06K 19/00743; G06K

19/07745; G06K 19/07747; G06K

19/07749; G06K 19/07758; G06K

19/07767; G06K 19/07769; G06K

(Continued)

(73) Assignee: **KIOXIA CORPORATION**, Tokyo (JP)
